(57) **CLAIM**

The ornamental design for a game device display, as shown and described.

DESCRIPTION

FIG. 1 is a perspective view of the gaming device display. FIG. 2 is a front elevational view of the gaming device display.

FIG. 3 is a back elevational view of the gaming device display.

FIG. 4 is a left side elevational view of the gaming device display.

FIG. 5 is a top plan view of the gaming device display; and, FIG. 6 is a right side elevational view of the gaming device display.

Broken lines illustrate features or environmental components that are not part of the design sought to be patented.
